UNITED STATES PATENT OFFICE.

HARRY PFANNENSTIEHL, OF MAPLEWOOD, NEW JERSEY, ASSIGNOR TO WESTERN ELECTRIC COMPANY, INCORPORATED, OF NEW YORK, N. Y., A CORPORATION OF NEW YORK.

PRINTING TELEGRAPHY.

Application filed April 8, 1922. Serial No. 550,646.

To all whom it may concern:

Be it known that I, HARRY PFANNENSTIEHL, a citizen of the United States, residing at Maplewood, in the county of Essex, State of New Jersey, have invented certain new and useful Improvements in Printing Telegraphy, of which the following is a full, clear, concise, and exact description.

This invention relates to printing telegraph apparatus and particularly to a unitary structure comprising a receiving printer and keyboard transmitter.

An object of the invention is to provide a telegraph receiver and transmitter combined as a unit wherein the necessary mechanical functions incident to the operation of the respective parts are performed in a reliable and efficient manner by mechanism operated positively.

Another object is the provision of a telegraph printer and transmitter combined in a unitary structure in which the power shafts of both the printer and transmitter are normally under tension, tending to rotate, and are controlled by friction clutches which are, in turn, controlled by the respective parts.

Another object is to provide a receiving printer and transmitter wherein the code combinations of message impulses may be transmitted solely through the instrumentality of mechanical movements either directly to line or through the winding of a relay to control the operation of the receiving printer for producing a home record.

The invention, according to one of its embodiments, provides a receiving printer in combination with a manually operable transmitting mechanism, having an electro-responsive device responsive either to selecting units received over a line or to the operation of the local transmitting mechanism; a manually operable transmitter operative solely through the instrumentalities of mechanical movements, a translating device controlled by the electro-responsive device for translating the effects of such units or impulses into mechanical movements and recording mechanism operable by such translated effects for causing the printing of the letters of the alphabet, numerals and other special characters on a printing medium.

The transmitting mechanism comprises a plurality of manually operable keys which cooperate with slidable members or bars adapted to be moved from their normal positions of rest whereby rocker arms are positioned selectively and are arranged to be actuated consecutively by cams to vibrate a single transmitting contact.

The electro-responsive device comprises a single electromagnet having its coils connected to the line conductor through the single transmitting contact controlled by the transmitting mechanism. This electromagnet responds to all impulses and, upon its initial energization, permits the operation of the translating mechanism.

The translating mechanism is made up of a series of rotatable and horizontally movable selecting rods which are successively brought under the control of the selecting magnet, there being a tripping finger individual to each rod. The tripping fingers are moved by the horizontal movement of the rods into a tripping and non-tripping position with respect to a series of latches depending upon the energization of the electromagnet which is energized in response to the impulses received. The selecting rods are, during the period of their selection, rotatable by power communicated to a shaft common to the selecting rods through a friction clutch, but subsequent to the release thereof and just prior to the engagement of the tripping fingers with the series of latches, a positive drive connection is established between the driving and driven shafts.

The recording mechanism comprises, among other parts, a flexible metal ring or wheel on one side of which the type representing the letters of the alphabet, numerals, punctuation marks, and other special characters necessary for the printing of a message, are embossed. The wheel or ring is rotatable in either direction through the shortest arc to bring the desired type into alignment with the printing hammer which, when operated, forces the ring with the type against the paper tape, the printing of the adjacent characters being prevented by a flexible shield. The type wheel is rotated by means of a rack and pinion normally under

tension by a helical spring and driven through a series of pivoted levers which are moved by crank levers under the control of a series of rotatable shafts for imparting to the type wheel a definite and predetermined degree of rotation. The series of shafts is controlled by the latches operated by the tripping fingers.

Referring to the drawings,

10 Fig. 1 is a perspective view of the mechanism as assembled;

Fig. 2 is a vertical sectional view with a portion of the casing removed;

15 Fig. 3 is a plan view with the top removed;

Fig. 4 is a vertical sectional view with the ribbon-feeding mechanism removed;

20 Fig. 5 shows the printer together with the keyboard sending mechanism from the left-hand side;

Fig. 6 is a perspective view of a portion of the selecting mechanism;

25 Fig. 7 illustrates the method of positioning the selecting rods in their two operative positions;

Fig. 8 is a plan view of a portion of the auxiliary selecting mechanism;

30 Fig. 9 is a detail view showing the shape of the releasing cams and their position with respect to the selecting rods;

Fig. 10 is an end view of the structure shown in Fig. 8;

Fig. 11 shows the mechanism of Fig. 10 in its inoperative position;

35 Figs. 12 and 13 illustrate two positions of the auxiliary selecting mechanism;

40 Figs. 14 and 15 are sectional views showing the manner of release and stopping of the shaft with which the selecting elements rotate;

Fig. 16 is a perspective of a portion of the driving gears;

Fig. 17 is a detail view of the type wheel;

45 Fig. 18 is a view taken along the broken lines 18-18 of Fig. 2;

Fig. 19 shows various positions of the stepping pawl for advancing the paper tape;

50 Figs. 20 and 21 show two positions of the lever arrangement for positioning the type wheel so that the characters P and 6, respectively will be in a printing position;

Fig. 22 is a sectional view taken along the broken lines 22-22 of Fig. 4;

55 Fig. 23 is a sectional view taken along the broken lines 23-23 of Fig. 4;

Fig. 24 is a detail view of the positive clutch;

60 Fig. 25 is a front view of the ribbon advancing mechanism in one of its operative positions;

Fig. 26 is a front view of the ribbon advancing mechanism in another of its operative positions;

65 Fig. 27 is a detail view of the ribbon ad-

vancing mechanism looking from the right of Fig. 26;

Fig. 28 is a perspective view of a portion of the type ring or wheel showing the arrangement of the flexible shield;

70 Fig. 29 is a front view of the parts shown in Fig. 28;

Fig. 30 illustrates the parts of Fig. 29 on an enlarged scale showing the manner of printing and shielding of the adjacent characters;

75 Fig. 31 shows a partial plan view of a key-board with the selecting elements of the distributing mechanism;

Fig. 32 is a sectional view taken along the broken lines 32-32 of Fig. 31;

Fig. 33 shows the mechanism illustrated in Fig. 32 in a different operative position;

80 Figs. 34 and 35 are sectional views taken along the broken lines 34-34 of Fig. 31 and show the selecting and selectable elements in their non-selecting and selecting positions, respectively;

85 Fig. 36 is a perspective view of a portion of the apparatus shown in Fig. 31, and

Fig. 37 illustrates the diagram of connections.

90 In Fig. 1 there is shown a perspective view of the printing mechanism in combination with the keyboard sender 6, having a metal base 1 upon which rests a casing or housing 2, which has a portion thereof hinged for the purpose of permitting easy access to the printing mechanism. In a circular opening in the top of the casing, there is positioned a wheel 3 upon which a paper tape 4 is wound.

95 Referring to Figs. 2 and 4, preferably the latter, a front view of the printer illustrating the arrangement of a plurality of pivoted levers 5, 6, 7, 8 and 9 are shown. Each of these levers is pivoted so that the distance through which they may be moved is different; that is, upon the movement of the lever 5 in either a downward or an upward direction, a member 10 will be moved through a given distance. Likewise, if the lever 6 is caused to move in either a downward or an upward direction due to the movement of the connecting link 12 or 13, the member 10 will be moved through a distance greater than that caused by the movement of the lever 5.

100 By arranging these levers in this manner, the various combinations of steps necessary for shifting or moving the type wheel from one position to another so that the different characters carried thereon may be brought into a printing position are effected. It is thus seen that one of the levers is designed to move the type wheel through a distance of sixteen steps

115 corresponding to a like number of characters, a second one through eight steps, a third through four steps, a fourth through two steps and a fifth through

95

100

105

110

115

120

125

130

one step. It is thus possible to position the type wheel in alignment with the tape or printing medium and the printing mechanism so that the printing of any desired character of the alphabet, numeral, or other special character, such as punctuation marks may be effected. Each of the levers or the connecting links 12, 13 and 30 is arranged with respect to a plate 11, which has a slot cut therein corresponding to each of these levers, so that an easy movement thereof with the least possible amount of friction results.

As shown in Fig. 22, which is a cross-section along the line 22-22 of Fig. 4, the connecting links are secured to the pivoted levers so that for each movement of the links 14, 15, 16, 17 and 18, there will be a resultant movement of the link 9, corresponding to the distance through which the associated lever is moved. The manner of connecting the links 30 and 31 with the pivot to which the pivot lever 5 is connected differs somewhat from that just described. This is illustrated in Fig. 23. Between the plate 11 and a surface of the lever 5, there is a washer 32 which holds this lever out of engagement with the member 11. The link 30 has one end thereof formed in the shape of a hook which fits over the end of the pivoted lever 5, while it is held in position by the enlarged portion of the link 31, the whole combination being held in place by means of a pin or other fastening means 33.

Rigidly secured to the member 10, which operates in a vertical plane, is a rack 26, shown in Fig. 17, which has cut on one edge thereof a series of teeth designed to engage the teeth of a pinion 27 rigidly secured to a shaft 28. The meshing of the teeth on the rack 26 with those of the pinion 27 is maintained by means of a roller 29. Disposed oppositely to the rack 26 is a second rack 36 which likewise has teeth on one edge thereof, which engage the teeth in the pinion 27. Similarly, this rack 36 is held in contact with the teeth on the pinion 27 by a roller 39. One end of the rack 36 extends into a hollow member 38 which has fitted therein a helical spring 37 so that the action of the helical spring in combination with the rack 36 places a tension on the pinion 27 so that during a portion of the operation, the rack 26 will have to work against the force exerted by the spring 37, thereby providing a more positive action and permitting of a more accurate positioning of the type wheel in alignment with the printing medium and printing mechanism.

Secured to the shaft 28 is a metal wheel 40 shown in Fig. 19 provided with a rim having cut therein a plurality of teeth of various depths, there being a tooth on the opposite side of each of the types. The

teeth in the rim of the wheel 40 individual to each of the characters are all of the same width and depth. The other teeth are provided for permitting of the various auxiliary operations such as spacing without printing, etc. These teeth are provided for the purpose of enabling the setting of the type wheel with respect to the printing mechanism and the tape or printing medium prior to the actual engagement of the printing hammer with the type wheel. Since it is sometimes desired to cause the advancement of the tape without causing the printing of a character, the depth of the teeth is not the same. Thus, as will be more clearly described hereinafter, the printing mechanism, because of the teeth in the rim of the wheel 40, is not permitted to go to its fullest extent for printing the character on the tape, but the mechanism is so arranged that the tape will be caused to advance one step.

Attached to the spokes of the wheel 40 is a type ring or wheel 41 on one side of which the various characters are embossed. The manner of mounting the type ring, which is provided with inwardly extending portions, is such that upon the engagement of the printing mechanism, a portion of the ring will be moved forward and upon its release will quickly restore to its normal position. For preventing the printing or smudging by the characters adjacent to the one being printed, a flexible steel ribbon 59 (Figs. 28, 29, and 30), having an aperture 69 cut therein which is in alignment with a printing anvil 54 attached to a plate 53, which, in turn, is secured to the upright 52, is provided. The steel ribbon 59 is attached at its ends to projections 67 and 76 and lies between an inking ribbon 182 and the paper tape 4. Upon the engagement of the printing mechanism with a portion of the type ring, the paper tape 4, as shown in Fig. 30, will be bent down over the edges of the anvil 54 while the inking ribbon 182 will be caused to pass through the aperture 69, one edge of which is cut in the shape of a V to prevent cutting of the inking ribbon and paper tape.

The selecting mechanism shown in Fig. 6 comprises a single selecting magnet 42 having a pair of oppositely disposed coils 43 and 44 which are supported on the frame 51. The coils 43 and 44 are arranged, when energized, to effect a movement of a pivoted armature 45 to one end of which there is secured a beveled extension 46. Since it is often desirable to connect the magnet directly in circuit with the line, thereby eliminating the use of a line relay, an extension pin 47 is secured to the armature 45 and serves as a fastening means for a spring 48, which extends between the extension pin 47 and the upright 49. One end of the spring 48 is fastened to a rotatable member 50,

which is fixed in an upright 49. This permits the adjustment of the tension exerted on the armature 45.

Normally when the selecting magnet 42 is used without the retractile spring 48, the armature 45 lies in a central position to the coils 43 and 44 so that the beveled extension 46 is in a position central to the space between a pair of deflecting fingers 57 and 58, shown in Fig. 7. These deflecting fingers 57 and 58 serve to guide the end of selecting rods 62 to 66. As shown in Fig. 6, these rods extend horizontally across the back of the machine, the extreme right end thereof being bent at an angle of approximately 90°. The movement of the selecting rods into their two operative positions is brought about upon their rotation, as will be more clearly understood from the following description, by the positioning of the beveled projection 46 on the armature 45 in the path of their movement, or, in other words, to one side or the other of the central position with respect to the deflecting fingers 57 and 58. In order that the selecting rods will be retained in the position set until a subsequent selection which requires them to be placed in the other of their operative positions, a semi-circular disc or locking vane 68 is mounted in a manner so that one end thereof, which like the extension 45 is beveled, lies in the central portion of the aperture between the deflecting fingers 57 and 58. Thus, if it is desired to position any one of the selecting rods from the right to the left of this disc in which position they will be in an operative position with respect to the other mechanism of the printer, the armature 45 must be moved so that the beveled extension 46 lies within the path of the projection on the rod next to engage this part, whereby it is moved either to the left or right of the semi-circular disc 68, depending upon which of the coils 43 or 44 is energized. Consequently, the selecting rod will be moved a distance equal to the thickness of the semi-circular disc 68, which distance is sufficient to permit of the satisfactory operation of the mechanism.

Individual to each of the selecting rods 62 to 66 and secured rigidly thereto are operated cams or tripping fingers 70, 71, 72, 73, and 74, shown in Fig. 9, which are of a shape such that though the rods to which they are secured are operated successively, they will function simultaneously. Fixed to each of the tripping fingers 70 to 74 is a circular plate 75, beneath which and movable therewith are a plurality of auxiliary selecting members or bars 78, 79, 80, 81, and 82, shown in Fig. 8, the free ends of which normally rest on a pin or roller 83. The selecting bar 80 is provided with a horizontally extending portion 84 so that for certain positions of the other selecting bars, the

free ends thereof, rather than resting on the roller 83, will be positioned on the extension 84, thereby establishing a condition similar to that which would be the case if they were resting or piled up on the roller 83, as shown in Fig. 8.

In order that the selecting rods may be revolved for successively positioning the various cams or tripping fingers in accordance with energization of the selecting magnet 42 for the desired character to be printed or other selecting purposes, the five rods are rotatable and freely movable in a horizontal direction in the bifurcated portion of a spoke-shaped member 60, which is rigidly secured to a driven shaft 61. The shaft 61 has power communicated thereto from a continuously running motor 90, shown in Fig. 3, the power circuit of which may be closed by the actuation of a snap switch 98 secured to the front of the machine, through worm gears 91 secured to the shaft of the motor and a pinion secured to the shaft 93. The worm wheel 92 is secured at one extremity of the operating shaft 93. This is secured at a point intermediate its ends to which are secured beveled gears 201 and 94, both of which normally tend to rotate due to the frictional engagement with friction discs disposed on opposite sides thereof. The beveled gear 94 engages a similar gear 97 secured to the end of the shaft 61 opposite to which the member 60 is secured. In order to vary the normal pressure between the friction discs 96 and the beveled gear 94, a plate 87 with a horizontally projecting portion having the free end thereof bifurcated, and a helical spring 89 disposed intermediate the plate 87 and a distance nut 88 are provided. Thus, by varying the pressure on the spring 89, a corresponding variation in the pressure existing between the various parts with which it is associated exists. Similarly, the beveled gear 201 is provided with means for varying the pressure exerted between the friction disc and one face thereof.

As will be more clearly described herein-after, the beveled gear 201 engages a beveled gear 202 through which power is communicated to a shaft 239, which drives the distributing mechanism of the keyboard transmitter.

Connected to the free end of the operating shaft of the motor 90, is a governor 203, which serves to regulate the speed of the motor 90 as is clearly understood by those skilled in the art.

During a portion of the revolution of the beveled gear 97, especially during the period that the selecting rods 62 to 66 are being positioned to one side or the other of the semi-circular disc 68, depending upon the energization of the selecting magnet 42, the load on the driving shaft 93, and consequently on

the beveled gear 94, is considerably lighter than that following such positioning of the selecting rods. It is necessary, upon an increase of the load, to provide a positive drive connection between the shaft 93 and the shaft 61 during the period that the tripping fingers 70 to 74 inclusive function. For providing this positive drive connection between these parts, a tooth wheel 85 is rigidly secured to the shaft 93, which is adapted to be engaged by a flexible spring 86 secured to the beveled gear 97, as shown in Fig. 24. The spring 86 is mounted with respect to the wheel 85 so that the engagement of these two parts is brought about following the setting of the selecting rods and continues until the tripping fingers have functioned, as will be more clearly described hereinafter.

Also secured to the shaft 61 is an irregular shaped stop arm 100, best shown in Figs. 14 and 15, which during the non-operation of the printers engages an extension on a member 101 pivoted to a member 102. One end of the member 101 engages the bifurcated portion of a bar 105, pivotally secured to a plate 108 to which there is also pivotally secured a latch 106. This latch 106 is normally held in position by a spring 107 secured to a portion thereof and the plate 108. The under-surface of the latch 106 has a notch cut therein which is adapted to receive one end of the bar 105, thereby retaining the extension on the member 101 in the path of the stop arm 100. By this arrangement the shaft 61 will normally be held against rotation, and will be released upon the initial energization of the selecting magnet 42. When the armature 45 is moved to the left and strikes against the latch 106, one end of this latch will be raised, causing the bar 105 to disengage the notch on the lower surface of this latch and moving the extension on the member 101 out of the path of the stop arm 100. Thus, since power is constantly applied to the shaft 93, as previously described, this shaft, together with the shaft 61 will continue to revolve until it is again stopped by the extension on the member 101. Just prior to the completion of the cycle of rotation of the shaft 61 and due to the engagement of the portion 99 of the member 101 with the irregular surface of the member 100, the member 101 together with the bar 105 and the latch 106 will be restored to their normal position, thereby placing the extension on the member 101 in the path of rotation of the stop arm 100. By this arrangement, the shaft 61 will be started into operation at the beginning of each signal period, and will be stopped following the positioning of the selecting rods necessary for the positioning of the character on the type wheel in alignment with the printing medium and the printing mechanism for effecting the printing of a desired character.

It is often desirous to permit orientation of the stop member with respect to the driven shaft so that the period intervening between the time that the initial impulse is received and the setting of the first selecting rod may be varied in order that the receiving mechanism will be in synchronism with the transmitting apparatus. This, in the present machine, is accomplished by providing a vertical member 104 pivoted to the rod 103 to which the member 102 is secured. By loosening the screw 77, the member 104 may be moved either to the right or left a distance determined by the circular slot formed in a portion of this member. Thus, since the member 101 is pivotally secured to the member 102, the time intervening between the release of the stop arm 100 and the engagement of the first selecting rod with the beveled extension 46 on the armature 45 may be varied while the printer is in operation.

In Fig. 6, mounted on the plate 110 and just in front of the cams or tripping fingers 70 to 74 inclusive, is shown a series of U-shaped members 111 and 112, each of which has pivoted thereto release latches 113 and 114. These latches are pivoted to the U-shaped members 111 and 112 in a manner so that they are positioned side by side, one being pivoted to the upper part of these members, while the other is pivoted to the lower part thereof and are thus operated independently of the other. They are held in their normal position by a spring 115. These latches, during the period that the printing mechanism is at rest, serve to retain a shaft individual thereto against rotation. The latches 113 and 114 are arranged to be moved out of the path of the shaft projection individual thereto by the cams of the tripping fingers 70 to 74, inclusive, depending upon the position of the corresponding selecting rod, and are arranged to permit the rotation of the corresponding shaft through an angle of 180°, as will be more clearly understood from the following description.

Corresponding to each set of release latches and extending horizontally from the back of the machine to the front thereof, are operating shafts 117, 118, 119, 120, 121, 115 and 122. Each of these shafts has one end thereof bent so as to engage one or the other of the release latches 113 and 114. At the extremity of these shafts, there are connected rectangular shaped pieces 20, 21, 22, 23, 24, and 25, to which the respective connecting links 14, 15, 16, 17, 18, and 19 are connected (Fig. 4). At a point intermediate the ends of each of these shafts, there is positioned a gear wheel 128, the teeth of which engage the teeth in the corresponding gear secured to the adjacent shaft (Fig. 3). Disposed on each side of these gear wheels is a disc of friction material 126 and 127, the former of which is secured by means of 130

a plate 123 having a horizontally extending portion, the free end of which is bifurcated and is secured in place by a locking nut 124. In order that the pressure between the disc 126 and the gear wheel 128 may be varied for different load conditions, a helical spring 125 is placed intermediate the plate 123 and the locking nut 124. Thus, by varying the position of the locking nut 124 on the associated shaft, the tension of the spring 125 may be varied. Disposed on the opposite side of the friction disc 127 is a gear wheel 129 which is rigidly secured to the respective shafts. This gear wheel has teeth arranged thereon for but a small portion of its periphery for the purpose, as will be more clearly described hereinafter, of forming a positive drive connection between the driving means and the shaft with which it is associated. Positioned beneath each of the gears 128, as is shown in Fig. 16, is an idler 132 fixed to the horizontally extending members 133 and 134, and engaging the teeth of the gears 129, and is provided for taking care of an increase in load following a selection. The idlers are held firmly in engagement with the teeth in the respective gears by a spring 130 secured at a point intermediate its ends in a manner to exert an upward pull on the shafts to which the idlers are secured. Power is communicated to the gears 128 and the idler gear 132 and their associated parts, as shown in Fig. 3, through a gear 136 rigidly secured to the shaft 93 which drives the gears 128 through an intermediate gear 135 which serves to reverse the direction of rotation of these gears with respect to the main driving gear 136. It is thus seen that since power is continuously applied to the shaft 93 from the constantly running motor 90, these gears will likewise be continuously revolved, but owing to the engagement of the projection at one end of the respective shafts with either the latches 113 or 114, these shafts are prevented from rotating. They will rotate, however, the instant they are released, on account of the frictional association of these gears with the friction discs 126 and 127.

Also secured to the shaft 93 is a gear wheel 137 which, like the gear wheel 128, drives an idler 146 shown in Figs. 5 and 18. Disposed on one face of the gear wheel 137 is a disc of friction material 147 which also engages a second gear wheel 138 and which has teeth formed thereon for only a small portion on its periphery for providing a positive driving connection between the idler 146 and the teeth thereon. To the opposite face of the gear 138 is rigidly secured a circular plate 139 in turn secured to a cam 140, which is normally retained against rotation because of its engagement by an extension on a rod 150, which extends across the back

of the machine, as is clearly shown in Fig. 6. Arranged beneath each of the release latches 114 and rigidly secured to the shaft 150 is an arm 151, which is operated upon the operation of any one of the release latches 114, causing the rotation of the shaft 150 through an angle sufficient to move the extension on the rod 150 out of the path of the cam 140. The cam 140 is fixed to a circular disc of friction material 141 which, like the friction disc 126, is held in engagement by means of the plate 143 in combination with the spring 144 and the locking nut 145.

When the extension on the rod 150 is moved out of the path of the cam 140, this cam, together with the gear 137, is free to rotate; and since power is communicated to the friction clutches 141 and 147 from the continuously running motor 90, the gear 137 will be rotated until the extension on the rod 150 again engages the cam 140. Following the release of the gear 137 and the cam 140, as is more clearly shown in Fig. 18, and following the positioning of the operating levers 5, 6, 7, 8, and 9, according to the particular selection chosen, the cam 140 allows arm 156, together with the roller 157 secured at one extremity thereof, to move in a downward direction, thereby causing a similar movement of the pivoted rod 160 which, in turn, causes the rotation of the irregular shaped rod 159. At one extremity of the rod 159 there is secured a printing mechanism or hammer 155 (Fig. 28), a portion of which engages teeth cut in the rim 40 for correctly aligning the type wheel 41 with respect to the extreme end of this mechanism. As previously described, the rim of the wheel 40 is provided with variously cut teeth. Those individual to the characters are, however, of the same shape so that upon the engagement of the member 155 with the walls of any of these teeth, any slight displacement of the type wheel 41 will be corrected.

An operating cam 172, controlled by the selecting rod 64, which carries the cam or tripping finger 72, is shown in Fig. 11. This cam is arranged to be rendered effective upon the positioning of the auxiliary selecting bars 78, 79, 80, 81, and 82 in either the position shown in Figs. 8 or 13, by the engagement of a pivoted bell crank 176, causing the operation of the release latches 173 and 174 which, like the release latches 113 and 114, are normally held by a coil spring 115. Similarly these latches control the rotation of the shaft 122, which extends to the front of the machine and controls the movement of the operating block 20 to which the link 19 is secured (Fig. 4). When the members 78, 79, 80, 81, and 82 are moved to the extreme right due to the positioning of the discs 75 with which they are as-

- sociated to such a position, the bell crank lever 176 will be fulcrumed at the free end of the member 82 so that upon the rotation of the selecting rods 64, together with the cam 172, controlled thereby, this cam will engage the opposite end of the bell crank lever 176, thereby causing the operation of either the release latch 173 or 174, depending upon whether the selecting rod 64 is positioned to the right or left of the semi-circular disc 68. Upon the operation of either of these release latches, the shaft is permitted to revolve through an angle at 180°, thereby imparting to the block 20 a similar degree of rotation, consequently causing the movement of the link 19 and the operating lever 9 to a position where the type wheel will be shifted from the portion carrying the letters to the portion upon which the figures and punctuation marks are formed, or vice versa, depending upon which one of the rods is operated. In cases where it is desired to shift the type wheel from one portion thereof to another and to effect the advancement of the tape one step, without causing the impression of a character, in one distinct operation, the auxiliary member 80 with its extension 84 is arranged so that when the members 78, 79, 80, 81, and 82 are in the position shown in Fig. 12, it is not necessary to effect the movement of all of these members, but only requires the movement of the member 80 by its corresponding disc 75. When the members are positioned as shown in Fig. 13 on the extension 84 rather than the roller 83, a condition similar to that just described will exist upon the rotation of the selecting rod 64 together with the operating cam 172. From the above description it is apparent that by means of such an arrangement, the type wheel may be shifted through a relatively large angle.
- The mechanism for causing the advancement of the tape 4 from a printed area to a non-printed area, as shown in Fig. 18, comprises among other parts, a ratchet wheel 177 fixed to a shaft 178 and a stepping pawl 169, the latter of which is secured to one extremity of an operating lever 168, which is pivotally secured to the member 167. The stepping pawl 169 is normally under tension of a coiled spring 170 having one end thereof secured to the stepping pawl 169, while the other end is secured to the member 168. The member 167 is rigidly secured to the operating rod 159 and normally tends to move in a downward direction due to the action of the spring 165 secured to this member and the rod 166; but, owing to the normal position of the operating rod 159, this member is prevented from moving. However, upon the movement of the operating rod 159, as previously described, the members 167 and 168, together with the pawl 169, will be caused to move in a downward direction, the former under the action of the spring 165, the latter under the action of the spring 170. The pawl 169, as shown by the dotted lines in Fig. 19, is moved into engagement with the next succeeding tooth on the ratchet wheel 177. Following the printing operation and the restoration of the operating rod 159 to normal, the members 167 and 168 and the pawl 169 are likewise restored to normal, and due to the engagement of the pawl with the next succeeding tooth, the ratchet wheel 177 will be caused to advance one tooth. Also secured to the shaft 178 is a pair of finely toothed wheels 179. Just above these wheels is a similar set of wheels 162 secured to a rod 163, which, under the action of spring 164, may be moved in an upward direction to cause the disengagement of the teeth in the wheels 162 with those in the wheels 179. A pin 198, Fig. 4, is fixed to the rod 163 and by a slight turn to the rod 163 when this rod has been raised a short distance, may be made to engage a notch 199 cut in the casing 200, which encloses the rod 163 and the associated spring 164. The tape 4 is designed to pass between the wheels 162 and 179 so that when the ratchet wheel 177 is advanced the distance of one tooth, a corresponding movement of the shaft 178 will be produced, causing the advancement of the tape 4 through a similar distance. A positive stop 171 is arranged so that the free end thereof lies in the path of the upward movement of the stepping pawl 169, thereby preventing the advancement of the ratchet wheel 177 through a distance equal to more than that of one tooth.
- It is often desired to cause advancement of the tape 4 without effecting the printing of a character. In the present invention, this feature is accomplished by advancing the type wheel through the setting of the selecting rods in a predetermined order whereby the type ring will be positioned so that one of the shallower cut teeth is in alignment with the printing hammer 155. Upon the movement of the printing hammer, as in the case previously described, when it was desired to advance the tape after the printing of a character, the shoulder 116 engages the outer edge of the tooth 152, shown in Fig. 19. In this case, the members 167 and 168 will be moved through a distance sufficient to permit the stepping pawl 169 to engage the next succeeding tooth on the ratchet wheel 177. But owing to the engagement of the shoulder 116 with the outer edge of the tooth 152, the extreme end on the printing hammer 155 will not be permitted to move far enough to engage the type wheel for the printing of a character. Thus, upon withdrawal of the printing hammer in the manner previously described, the stepping pawl 169 will be restored to its normal position against the

positive stop 171, thereby rotating the ratchet wheel 177 through a distance equal to one tooth. Consequently the tape 4 will be advanced a similar distance. Should the type 5 wheel be in a position whereby the shoulder 116 on the printing hammer 155 engages the outer edge of the tooth 161, neither printing nor advancement of the tape will be caused since the stepping pawl 169 is not moved far 10 enough to permit its engagement with the next succeeding tooth in the ratchet wheel 177, as is clearly shown in Fig. 19 and is represented by the dotted lines 169^a.

The mechanism for advancing the inking 15 ribbon continuously, as illustrated in Figs. 25, 26, 27, comprises a pair of ribbon spools 180 and 181 upon which the inking ribbon 182 is wound and which are arranged one above the other and revolvably supported 20 by arms 185 individual thereto. Individual to each of the spools 180 and 181 are gear wheels 186 and 187 respectively, which serve upon the engagement thereof with the teeth in a worm gear 188 secured to a shaft 187 for 25 causing the advancement of the inking ribbon. Secured to one end of the shaft 189 is a beveled gear 190, the teeth of which mesh with those of a corresponding beveled gear 191, which is secured to the shaft 93 driven 30 from the continuously running motor 90.

As shown in Fig. 27, the shaft 189 is mechanically locked in a position whereby the teeth of the worm gear 188 mesh with the gear wheel 186 or 187, depending upon the 35 position of the end of this shaft with respect to the extending portion 193 of the vertically supported member 192. For preventing the accidental movement of this shaft from its two operative positions, a 40 spring member 194 pivoted to the vertical member 192, is provided, which may be readily moved to permit the positioning of the shaft 189 in either of its two operative positions. Attached to one end of the worm 45 gear 188 is a projection or shoulder 184 which, under normal conditions is unrestricted against rotation. Pivotally mounted to the plate to which the member 185 is secured are members 195 and 196 each of 50 which has a slot, shown in Fig. 2, cut in one end thereof and through which the inking ribbon is designed to pass. However, upon the movement of either of the pivoted members 195 or 196, each of which is held in its 55 normal position by spring 197, due to the engagement by a button 183 secured at a point near each end of the inking ribbon, the engaged member will be rotated through an angle sufficient to cause the opposite end thereof to lie in the path of the shoulder 184. Thus, upon the continued rotation of the 60 worm gear 188 and due to the cam action caused by the movement of the member opposite to the one in engagement with the 65 button 183 into the path of the shoulder 184

the worm gear 188 will be moved from engagement with the teeth on one of the gear wheels 186 or 187 to engagement with the other gear wheel.

As shown in Fig. 2, the button 183 secured to the ribbon 182 is about to engage one extremity of the member 195 and upon the engagement of this button with this member and due to the fact that the slot, through which the inking ribbon passes, is not large enough to permit the passage of the button 183, the member 195 will be rotated a distance sufficient to cause the lower extremity of this member to engage the shoulder 184, thereby causing the worm gear 188 to engage the teeth in the gear wheel 187 and engage those in the gear wheel 186 for reversing the direction of travel of the ink ribbon. Immediately following the disengagement of the button 183 with the member 195, this member will be restored to its normal position under the action of spring 197.

In the illustrated embodiment of the invention, the keyboard mechanism, as shown in Fig. 31, is arranged according to an ordinary typewriter, each key being capable of independently performing the selecting operations required to position selectable elements to produce the desired selecting operations. Each key lever 207 is pivoted to the arm 208 with springs 209 normally tending to elevate the outer end thereof. The springs and pivots, although not shown in detail are similar in construction to the arrangement disclosed in Patent No. 1,229,201, which issued January 5, 1917. Each key lever has, toward the rear end thereof, a knife-like portion 206 serving to move, upon the actuation thereof, the selecting elements in varying combinations.

Situated directly above and extending in a direction transverse to the key levers 207, Fig. 31, are six selectable selecting members 211, 212, 213, 214, 215, and 216 and a stationary member 217. The base 208 has secured thereto guide members 218 and 219, which serve to support and guide the members 211 to 216, inclusive. Each of the selecting members 211 to 216, inclusive has on one edge a different arrangement of downwardly projecting beveled edges 220 so that these members will be moved in varying combinations according to the key lever depressed. When any one of the key levers is depressed, the knife edge 206 engages the beveled projections 220 on the selecting members so that these members will be moved in a direction transverse to the position of the key levers in accordance with a predetermined arrangement. The selecting member 211, however, moves upon the depression of any one of the key levers for affecting certain selecting operations and is provided at one extreme thereof with a stop 130

221 and a member 222 provided just above the stop 221, one surface of which is inclined slightly.

As shown in Fig. 36, each of the selecting members 212 to 216 inclusive, has cut on the upper surface at one end thereof, notches 223 in which an operating link normally rests, there being an operating link individual to each one of these members. The links 228 to 233 inclusive, are pivoted to a revolvable bail 234 supported by bars 235 and 236, which are, in turn, fixed on a rod 237 and a bail 234.

Situated directly beneath the other end of the operating links 228 to 233, inclusive, are a series of cams 244 spaced equally distant along a shaft 239 and separated by metal discs 225 so that upon rotation of the shaft, the operating links will be engaged by their associated cams for effecting their movement consecutively. The cams and metal discs are held in position by means of bushings 238 and 246 which are rigidly secured to the shaft 239. Normally, the shaft 239, having secured at one extremity thereof a beveled gear 240, which engages a similar gear 241 secured to a vertically mounted shaft 242 tends to rotate. Likewise the shaft 242 has secured to the end opposite to that to which the gear 241 is secured, a second gear 258 which engages a beveled gear 257 driven by power communicated to the beveled gear 202 by the gear 201, as shown in Fig. 5. The shaft 239 is restrained against rotation by the stop 243 rigidly secured to the shaft 239 engaging the stop 221 which, as previously described, is secured to the selecting member 211.

Mounted directly above bail 234 and in a position central thereto and arranged to be engaged by a circular disc 227 is a single transmitting contact 245. This contact 245, when the shaft 239 is at rest, engages a contact screw 247, owing to the bail 234 being raised on account of one end of the operating link 233 being fulcrumed on the member 217 and the other end thereof being in engagement with the associated cam on the shaft 239. The contact spring 245 is also provided with a contact terminal 248, which may be either connected directly to battery or ground, as the case may be, or through the winding of the selecting magnet 42 of the printing mechanism, while the contact 247 may be permanently connected to a line conductor 261 extending to a distant station over which it is desired to transmit the desired code combinations of message impulses in accordance with the depression of the desired key 207. The contact 247 may be also connected to the line 261 through a line relay, as shown in Fig. 37. Moreover, the double-polarity system may be used with equally good results in which the contact spring is normally in contact with marking

battery while spacing battery is connected with the opposite contact and with which the contact may be moved to change the polarity of the current applied to the line conductor.

At a point intermediate the ends of the selectable members 212 to 216 inclusive, as shown in Fig. 32, a pair of notches 250 and 251 is cut, the intervening portion thereof being formed in the shape of a knife edge to more readily permit of the movement of a downwardly and horizontally projecting portion 256 of a locking bar 252. Bar 252 is pivoted to the rod 253 and has an extending portion which is arranged to be engaged by a cam 255 on the shaft 239. During the period that the shaft 239 is at rest, the projecting portion 256 of the member 252 is withdrawn from the slots 250 and 251, thereby permitting of their movement. However, the instant that the shaft is set in rotation, the projecting portion 256, due to the moving of the cam 255 out of engagement therewith and to the action to a coil spring 254, is drawn into engagement with the slots 250 or 251 depending upon the position of the selecting members 212 to 216, inclusive, thereby locking the members in position to prevent the depression of any of the key levers 207, while the shaft 239 is revolving and consequently the mutilation of signals.

The receiving printer hereinbefore described is operated preferably by various combinations of five selecting current units with an additional impulse preceding the selecting units for conditioning what may be termed the distributing mechanism of the receiving printer for operation. Impulses may arrive over the line and pass through the customary line relay having both front and back contacts. In this case the windings of the coils 43 and 44 are connected to these front and back contacts. In some cases it may be advisable to eliminate the line relay and to use but one set of coils of the selecting magnet 42 as is more clearly shown in Fig. 32 and to normally bias the armature of the selecting magnet by the use of the spring 48.

The operation of the transmitter and printing mechanism hereinbefore described relative to a particular type selection and the operations incident thereto are as follows: For the sake of clearness, let it be assumed that it is desired to transmit and print the character P. Further assume that the character P comprises the following selecting current units: no current, current, current, no current and current. Also assume that the type wheel 41 is in a position for the printing of the characters of the alphabet. The key 207 corresponding to the character P having been depressed, the common member 211 is moved in the direction of the arrow, thereby moving the stop 221

out of the path of the stop arm 243, and since power is communicated to the shaft 239 through a friction clutch, this shaft will be revolved. As previously stated, the contact spring 245 is normally in engagement with the contact 247. However, the instant the shaft 239 is set in rotation, the cam associated with the operating link 233 moves out of the path thereof, thereby allowing the bail 234 with the disc 227 to drop and consequently open the circuit between the contact spring 245 and contact 247, thus transmitting what is known as a start impulse. The opening of the circuit in this manner causes the deenergization of the line relay 300, Fig. 37 and the transmission over the line 261 of a start impulse.

Also immediately following the setting of the shaft 239 into rotation, the member 252 is moved so that the projection 256 engages one or the other of the notches 250 and 251 in the selecting members 212 to 216, inclusive, depending upon the position of these members, thereby preventing their movement until the present selection has been cleared out. Let it also be assumed, for the sake of clearness, that the selecting members 213, 214, and 216 for the transmission of the selecting units representing the character P, have been moved in the direction of the arrow while the remaining selecting members remain in the opposite position. As the shaft 239 continues its rotation, the selecting member 212 being in the position shown in the drawing, the end of the operating link 228 remains in the notch of the selecting member 212 so that upon the engagement of its associate cam therewith, the contact spring 245 will be allowed to disengage contact 247 so that an open circuit condition will be established with the line. A condition similar to that just described will take place upon the engagement of the cam individual to the operating link 231 associated with the selecting member 215. As the shaft 239 continues its rotation, the selecting member 213 having been moved in the direction of the arrow, the end of the operating link 229 now rests upon the upper surface of the selecting member 213 so that upon the engagement of the associate cam with the link 229, one end of this link will be fulcrumed on the member 213, thereby raising the bail 234 and effecting a closure between the contact spring 245 and the contact 247. A condition similar to the one described in connection with the selecting member 213 will be established upon the engagement of the cam individual to the operating links 230 and 232, respectively, as the selecting members are moved so as to form a fulcrum for their respective operating links. It is, of course, to be understood that the line relay 300 responds to such actuation of the contact spring 245 and causes

the corresponding energization, as will be more clearly described hereinafter, of the coils 43 and 44 of the selecting magnet 42 of the recording mechanism, causing the printing of the character corresponding to 70 the actuation of the key levers. In this way a home record is made of the messages transmitted from the keyboard.

Following the engagement of the associate cam with the operating link 232, the cam individual to the operating link 233 causes the bail 234 to be lifted as the other end of this link is fulcrumed on the stationary member 217, thereby closing the contact between contact spring 245 and contact 247 for transmitting a releasing impulse over the line 261 or in other words, establishing the line to its normal condition. Just prior to the completion of the cycle of rotation of the shaft 239, the cam associated with the member 252 engages the projection thereof, thereby lifting the projecting portion 256 out of engagement with the notches 250 or 251 and in turn permitting the setting up of a new selection. 90

In order to prevent the letters from being repeated should a key lever be depressed for a period longer than the time required for the shaft 239 with its associated cams to complete one cycle, the member 222 having an inclined surface, is arranged just above the stop 221 so that should the key lever be held down, the stop arm 243 will stop against the inclined surface until the key lever has been released at which time it will move 100 into engagement with the stop 221.

The operation of the printing mechanism for the printing of a home record, as well as similar printers connected to the other end of the line 261, is as follows: The opening of the line circuit, as previously described, transmits a starting unit, which, in the present case, amounts to opening the line whereby the line relay 300 is deenergized, thereby causing the energization of the coils 43 of the selecting magnet 42. The energization of the coils 43 of the selecting magnet 42 causes the reversal of the position of the armature 45 whereby the release latch 106 is rotated about its pivot, thereby causing the disengagement of the bar 105 with the notch on the under surface of this release latch. The release of the bar 105 causes the member 101 to be rotated about its pivot a distance sufficient to move the extension on this member out of the path of the stop arm 100 secured to the shaft 61. The instant the member 101 is moved in this manner, the shaft 61, together with the stop arm 100 is free to rotate since, as previously described, power is communicated to this shaft from a continuously running motor 90 through friction clutches associated with the bevelled gear 94. 110

The first selecting unit of the combination 120

being no current the line relay 300 remains deenergized thereby maintaining the coils 43 of the selecting magnet 42 energized until the position of the armature of relay 200 is again reversed. The shaft 61 together with the selecting rods 62 to 66 inclusive, now being rotated, causes the projections on these rods to successively engage the bevelled extension 46 on the armature 45. Inasmuch as coils 43 are energized for the particular selection in question, the armature 45 will be in a position whereby the projection on the selecting rod 62 will be moved to the right of the semi-circular disc 68, thereby causing a similar displacement of the cam or tripping finger 70 with respect to the release latches 113 and 114, placing it in a position to operate the release latch 113 upon its continued rotation. Upon the transmission of the second selecting unit, which consists in applying a source of current to the line 261, the line relay 300 will be energized. The coils 43 will be deenergized thereby and the coils 44 of the selecting magnet 42 energized for reversing the position of the armature 45. Thus, the bevelled extension 46 will be moved to the right so that upon the engagement of the projection on the selecting rod 63 with this bevelled extension it will be deflected to the left of the semi-circular disc or locking vane 68, and consequently will move the selecting rod 63 and the cam or tripping finger 71 a distance equal to the width of this disc or locking vane. The next selecting unit being current, the line relay 300 remains energized thereby retaining the armature 45 in its extreme right position. Consequently the projection on the selecting rod 64, like that of 63, will be moved to the left of the semi-circular disc or locking vane 68. For the next selecting unit, the line relay 300 is deenergized, causing the energization of the coils 43 of the selecting magnet 42 and the reversal of its armature, so that upon the engagement of the projection on the selecting rod 65 with this bevelled extension the selecting rod 65 together with the cam or tripping finger 73 will be moved to the right a distance equal to the thickness of the semi-circular disc or locking vane 68. The last selecting unit being current, the line relay 300 is energized, causing the energization of coils 44 and the reversal of the position of the armature 45. Upon the engagement of the projection on the selecting rod 66 with the bevelled extension 64, the rod 66 will be moved to the left and retained in such position until a succeeding selecting unit is transmitted which reverses its position with respect to the semi-circular disc or locking vane 68.

Following the positioning of the selecting rods in the manner just described, the cams or tripping fingers 70, 71, 72, 73, and 74 will

be in a position so that they are just about to operate the corresponding release latch at which time the flexible spring 86, as shown in Fig. 24 will be approaching the teeth in the gear wheel 85. During the 70 operation of the release latches 113 and 114, it is necessary to provide a positive drive connection between the shaft 61 and the shaft 93, as at this time the greatest load is exerted on the motor 90. Assume also that 75 the projections on the shafts 118, 119, and 121 are in engagement with the upper or release latch 113, while the extensions on the shafts 117 and 120 are in engagement with the release latch 114. Then, since only one 80 of the latches 113 and 114 is designed to be released by the operating cams or tripping fingers 70 to 74 when the corresponding selecting rod is moved either to the right or left with respect to the semi-circular disc 85 68, the shafts 117 to 121 will be released for rotation simultaneously upon the engagement of the tripping fingers 70 to 74 with the release latch retaining the respective shaft against rotation. In this case these 90 shafts will be rotated through an angle of 180 degrees due to the frictional engagement of the friction discs 126 and 127 with the continuously running gear 128, thereby moving the operating levers 5, 6, 7, and 8 to 95 the position shown in Fig. 20.

For the first few degrees of rotation of the shafts 117 to 122 inclusive, no appreciable load is applied to the friction clutches 126 and 127, but is only noticeable between 100 approximately the first and last 15 degrees of rotation during which period considerable slippage takes place between the several gears and the friction discs owing to the increase in load. To obviate this condition, a positive drive is completed between the respective parts by the use, as previously described, of gear wheels 129, which have teeth formed on the periphery thereof for only a portion of the circumference. Thus, during the period of increase in load, the teeth in the gear wheel 129 engage those in the idlers 132, thereby establishing a positive drive connection for lessening the load on the friction clutches individual to the 110 respective gears 128.

The movement of the operating levers 5, 6, 7, and 8 and consequently the lever 9 will cause the rack 26 to be moved together with the pinion 27 and the shaft 28 to a distance to properly position the portion of the type ring carrying the character P in alignment with the printing medium and the printing hammer 155. Upon the operation of any 120 one of the release latches 114, the member 151, pivoted to the shaft 150, is operated, thereby rotating its associated shaft through an angle sufficient to cause the removal of the extension thereon from engagement with the cam 140, which is then free to revolve 125 130

through the frictional engagement of the gear 137 with the friction discs 141 and 147. The roller 157, together with the arm 156 upon the continued rotation of a cam 140, falls into the depressed area, more clearly shown in Fig. 1, for causing the rotation of the rod 153. However just prior or about the time when the roller 157 is engaging the depressed area on the cam 140, the teeth on the wheel 138 which, as previously described, has teeth thereon for but a small portion of its periphery, engage the idler 146 and provide what may be termed a positive drive connection for rotating the cam whereby a more positive connection is produced on the rod 153. As the rod 153 continues to rotate, the operating rod 159 is rotated about its pivot so that the printing hammer 155 presses the portion carrying the character P, as shown in Fig. 30, against the paper tape and thus effects the printing of this character.

Before the character is printed, however, the type ring will be aligned with the extreme end of the printing hammer due to the engagement thereof with the side of the teeth cut in the rim of the wheel 40, as was previously described.

At the time that the printing hammer 155 is printing the character P on the tape 4, the stepping pawl 169 has engaged the next succeeding tooth of the ratchet wheel 177 so that upon the withdrawal of the printing hammer 155 from engagement with the type ring, the members 167 and 168 will be restored to their normal positions, thereby causing the advancement of the ratchet wheel 177 through the action of the stepping pawl 169 one tooth. Consequently, the paper tape 4 will be advanced to position an unprinted area before the type wheel 41.

As the stop arm 100, together with the shaft 61 continues its rotation and just prior to the completion of the cycle thereof, the portion 99 of the member 101 engages the irregular surface of the stop arm 100, thereby causing the restoration of the release latch 106, the operating bar 105 and the member 101 to their normal positions or the position shown in Fig. 6. Thus, before the stop arm 100 has completed its cycle of rotation, the projection on the member 101 will lie in the path of this arm thereby arresting the rotation of the shaft 61 after it has completed its cycle of rotation. The paper tape 4 in travelling from the reel 3 to the point of printing, moves over a roller 109 secured to the free end of a horizontally projecting member 131 which serves to accurately guide the paper.

Assuming that it is desired to shift the type wheel 41 from the portion carrying the letters of the alphabet to the portion on which the figures or other special characters are mounted, it is necessary to operate

the key of the keyboard transmitter designated as the shift key for the transmission of a definite series of selecting units. Such a series of selecting units is as follows: current, current, no current, current, and current. Inasmuch as the operation of the keyboard sender is identical with that of the transmission of the selecting units corresponding to the character P, a further discussion of the operation of this part of the mechanism is considered unnecessary here. The selecting magnet 42 in responding to such impulses causes all of the selecting rods, with the exception of the one carrying the cam or tripping finger 72 to be positioned to the left with respect to the semi-circular disc or locking vane 68. With such a setting of the selecting rods, the auxiliary selecting members 78, 79, 81, and 82 will be in a position so that the free ends thereof will be arranged as shown in Fig. 8. It is, of course, understood that the stop arm 100 has been released for rotation, as was described in connection with the positioning of the type ring 41 for the printing of the character P. As the shaft 61 continues to rotate following the setting of the selecting rods in the manner just described, the lower end of the bell crank lever 176 engages a surface of the member 82 which has been positioned in this manner by the setting of the selecting rods 62, 63, 65, and 66 to the left with respect to the semi-circular disc or locking vane 68. Due to the engagement of the lower portion of the bell crank lever 176 in this manner, the cam 172 controlled by the selecting rod 64 is caused to rotate about its pivot and since the selecting rod 64 is in its extreme right position, the latch 173 will be operated upon the engagement of the cam 172 therewith so that the shaft 122 will be free to rotate until arrested due to the engagement of the extension thereon with the release latch 174 positioned at an angle at 180° from the release latch 173. The shaft 122 will thus be revolved in a manner similar to that described in connection with the other shafts. Due to the accumulated effect produced by the positioning of the operating blocks 20, 21, 22, 23, 24, and 25, the rack 26 will be moved a distance sufficient to impart a rotary motion to the pinion 26 such that the type wheel 41 will be rotated through an angle sufficient to position that portion of the type wheel carrying the figures and other special characters in alignment with the printing mechanism.

Following the positioning of the type ring 41 in the manner just described, assume that it is desired to print the numeral 6. The character key 207 corresponding to the numeral 6 would thus be depressed for transmitting the following set of selecting units: no current, current, no current, current, and

no current. The electromagnet 42 in responding to these impulses, causes the selecting rods upon their rotation to be positioned in a manner whereby the respective cams or tripping fingers 70 to 74 are in a position whereby upon the operation of the corresponding release latch, the shafts 117, 118, 119, 120, 121 will be rotated so that the rectangular block secured at one end 5 thereof will assume the position shown in Fig. 21. With the operating levers 5, 6, 7, 8, and 9 in the position shown in this figure, the numeral 6 will be in alignment with the projection on the printing hammer 155. The printing of the numeral 6 is effected in a manner similar to that described in connection with the printing of the character P. A further description of the operation of the system in this respect is, therefore, considered unnecessary.

If it is desired to unshift the type ring as, for example, from the portion on which the numerals or other special characters are mounted to the portion carrying the letters 25 of the alphabet, the transmitting mechanism will be operated for transmitting the following series of selecting units: current, current, current, current, and current. As before, the selecting rods 62, 63, 65, and 66 30 will be positioned to the left with respect to the semi-circular disc 68. Likewise, the selecting rod 64 will be positioned to the left with respect to the semi-circular disc 68. The selecting rod 64 being thus moved to 35 the left, the cam 172 upon the engagement thereof with the bell crank lever 176 and due to the arrangement of the auxiliary selecting members 78, 79, 81, and 82 in the position shown in Fig. 8, the release latch 40 174 will be operated upon the continued rotation of the selecting rods. Consequently the shaft 122, the projection of which is now in engagement with the release latch 174 will be revolved until arrested by the release latch 133 or to the position shown 45 in Fig. 11. Due to the setting of the selecting rods in the position just described and the rotation of the shafts 117 to 122 inclusive, to a position whereby the rectangular blocks 20 to 25 inclusive, are in the position 50 shown in Fig. 4, the type ring 41 will be in a position for the printing of the characters of the alphabet.

It often becomes necessary to shift the type wheel from the area thereof carrying figures or other special characters to the area carrying the letters of the alphabet and also advance the tape 4 with one separate and distinct operation. To accomplish this, it 55 is necessary to operate the unshifted key of the transmitter for transmitting a series of impulses or selecting units whereby the selecting rods will be positioned so that the auxiliary selecting rods 78, 79, 80, 81 and 82 60 assume a position similar to that shown in

Fig. 13. Thus, as the selecting rods are revolved, and due to the engagement of the bell crank lever 176 with the end of the auxiliary member 82, which is now raised as shown in Fig. 13, the cam 172 will be 70 caused to engage the release latch 174. The auxiliary shaft 122 will be free to rotate through an angle of 180° upon the operation of the release latch 174. In this manner the type wheel 41 will be rotated through a relatively large angle, that is, the portion of the type wheel carrying the letters of the alphabet will be positioned in alignment with the printing mechanism. Likewise, the rod 153 will be rotated, as previously described, for 75 causing the stepping pawl 169 to engage the next succeeding tooth in the ratchet wheel 177 for imparting to the shaft 170 a degree of rotation sufficient upon the restoration of the stepping pawl to normal to advance the tape 4. No character is printed as the type wheel is in a position such that the shoulder 116 of the printing hammer 155 80 engages a tooth similar to that designated 85 by the numeral 152.

Although the present invention has been disclosed and described in connection with a particular combination of receiving printer and keyboard transmitter, it is, of course, obvious that several of the embodiments of the invention may be incorporated in other types of mechanisms without departing from the spirit and scope of the invention.

The invention claimed is:

1. The combination in a unitary printing 100 telegraph transmitting and receiving mechanism of a transmitting contact, a plurality of key levers, an all-mechanical distributor, code selecting bars set by said levers for controlling said distributor, a power shaft for 105 driving said distributor to actuate said contact, a receiving magnet responsive to impulses sent by said contact, a set of rotatable combination rods arranged to be displaced horizontally by said magnet, a series of 110 translation levers controlled by said rods, a type wheel rotatable in response to the cumulative action of said translation levers to present a desired type for printing, a second power shaft for rotating said combination 115 rods and for actuating said translation levers, and a common motor for driving both of said shafts.

2. The combination in a unitary printing 120 telegraph transmitting and receiving mechanism of a single transmitting contact, a plurality of key levers, a mechanical distributor comprising a series of levers, code selecting bars having notches therein and arranged to be actuated by said key levers for storing signal combinations, a power shaft normally tending to drive said distributor to actuate said transmitting contact by means of said second mentioned levers in accordance with 125 the setting of said code selecting bars, a re- 130

- ceiving magnet responsive to signal impulses sent by said transmitting contact, a set of rotatable combination rods arranged to be displaced horizontally in both directions by the 5 armature of said receiving magnet, a set of translation levers actuated in accordance with the settings of said combination rods, a type wheel rotatable in response to the cumulative action of said translation levers to 10 present a desired type of printing, a second power shaft for rotating said combination rods and for actuating said translation levers, and a common driving motor for actuating both of said shafts.
- 15 3. A printing telegraph transmitting and receiving mechanism combined into a single unitary structure and comprising a single transmitting contact, a plurality of key levers, code selecting bars actuated in combinations in accordance with the key lever depressed, a mechanical distributor comprising 20
- 25 a series of contact operating levers cooperating with said code bars to actuate said transmitting contact, a power shaft having a series of cams thereon cooperating with said contact operating levers, a receiving magnet responsive to signal impulses from a distant station or sent by said transmitting contact, a rotatable shaft having a series of selecting rods arranged thereabout and movable horizontally in various combinations in response to the operation of said receiving magnet, a translating mechanism actuated in accordance with the setting of said selecting rods, a type wheel rotatable in accordance with 30 the actuation of said translating mechanism for presenting a desired character for printing, and a common driving motor for actuating both of said shafts.
- 35

In witness whereof, I hereunto subscribe my name this 3rd day of April A. D., 1922.

HARRY PFANNENSTIEHL.
